UNITED STATES PATENT OFFICE.

CHARLES L. STOKES, OF LOS ANGELES, CALIFORNIA.

LIQUID-FEED SYSTEM.

1,230,596.

Specification of Letters Patent. Patented June 19, 1917.

Application filed September 14, 1916. Serial No. 120,069.

To all whom it may concern:

Be it known that I, CHARLES L. STOKES, a citizen of the United States, residing at Los Angeles, in the county of Los Angeles, 6 State of California, have invented new and useful Improvements in Liquid-Feed Systems, of which the following is a specification.

This invention relates to systems for feeding or lifting liquids; and, in its more particular phase, hereinafter described, relates to systems for feeding liquid fuel for internal combustion engines of any type,—either stationary engines or in automobile 15 or marine installations or the like. It is a general object of this invention to provide a system of liquid feed which involves a simple mechanism or structure, and is automatic in its operation. And it is specifically 20 the object of the invention to provide a fuel feed system for internal combustion engines, etc. to be operated by suction (from the engine intake) to lift fuel from a tank located at a lower level to feed the carbureter; 25 to be automatic in its operation; and to be so constructed and so operated as to continue its operation under any conditions or positions in which the parts may be relatively placed, without shutting off the supply of 30 liquid fuel or without flooding the auxiliary or service reservoir and the carbureter. It is an object of this invention to provide a simple and effective means for controlling the application of suction to fill the reservoir. It is one of the specific objects of 35 this invention to provide a means for automatically controlling the passage of liquid from the main tank to the service reservoir, in such a manner that, no matter what may 40 be the relative positions of the parts, the service reservoir may be charged only to a certain level.

In my co-pending application S. N. 91303 filed April 15, 1916 I explain the general 45 features of a liquid fuel lifting system utilizing air in the lifting line; said air, after separating from the liquid, going to the engine as carbureted air. In said application I describe a continuously operating 50 system, wherein the liquid fuel is continuously raised by suction and surplus fuel is returned to the main tank; and in said application I lay claims broadly to the mechanism for admission and use of air 55 in the manner specified. In this present

application I explain a mechanism which operates upon the same general principle, using air in the lifting line, but which is intermittent in its operation; means being provided to control the fuel lifting operation in accordance with the amount of fuel in the service reservoir.

Other objects of this invention will appear in the following detailed specification, wherein I explain a preferred form of my apparatus as applied to an automobile or the like, reference being had to the accompanying drawings, in which, for the purpose of this specification, I have illustrated said preferred form. In said drawings, Figure 70 1 is a diagram showing the various operative parts of the apparatus of my system, and showing their relations and connections; Fig. 2 is an enlarged detail section of the connection to the main fuel tank; Fig. 75 3 is an enlarged vertical section of the service reservoir; and Fig. 4 is a section of the same taken as indicated by line 4—4 on Fig. 3. It will be understood that, although I illustrate an arrangement of parts typical 80 of an automobile installation, the system herein described and shown is equally applicable to any internal combustion engine plant.

In the drawings I show an ordinary fuel 85 tank at 10, representing the fuel tank usually located at the rear end of an automobile. In a stationary installation the tank may be located underground. This tank has the usual filling opening 11 with an air 90 vent; and has an outlet 12 at its bottom. Outlet 12 leads into a chamber 13 from which a feed pipe 14 leads horizontally and upwardly to the service reservoir 15. Within the chamber 13 there is an air jet nozzle 16, supplied with air through a pipe 17 whose open upper end 17^a is above the level of the liquid in tank 10. The relative sizes of pipe 14, outlet 12, and nozzle 16 are such that when suction is applied to pipe 14 the 100 liquid will be drawn from tank 10 and air will also be drawn through the nozzle 16; creating a mixture of liquid and air in the pipe 14. This mixture of liquid and air is lighter than the liquid itself and is 105 consequently drawn through pipe 14 by a minimum application of suction. Pipe 14 discharges into the service reservoir 15. The inlet passage 20, through which pipe 14 discharges into reservoir 15, is controlled by 110

an upwardly closing fuel valve 21 mounted upon or connected to a float 22; the arrangement being such that, when the liquid level L in the reservoir rises to a certain predetermined point, this fuel valve 21 will close and will prevent further discharge of liquid into the reservoir under any condition. The upper part of the reservoir is connected by suction pipe 23 with the intake manifold 24 of the engine, above the throttle valve 25 so as to get the benefit of the maximum engine suction. The carbureter C may be of any kind, of the conventional float type, with the fuel reservoir open to atmosphere. The liquid fuel is fed from service reservoir 15 through the pipe 30 to the carbureter C, this pipe having in it an upwardly opening check valve 31. It is the function of this check valve 31 to prevent back passage of liquid from the carbureter to the reservoir under certain situations, hereinafter described.

The service reservoir 15 has an air inlet at 35 controlled by a small air valve 36. Air entering at 35 flows into the hollow interior 37 of the valve plug and thence out through ports 38 and 39 into the interior of the reservoir, when ports 38 and 39 are in registration. The valve arm 40 is engaged by an upwardly facing shoulder 41 of a member 42 when the float 22 moves up toward its position illustrated; and is engaged by a downwardly facing shoulder 43 when the float moves down toward the bottom of the reservoir, and when the liquid level has reached near the bottom. In the position illustrated, the air valve 36 is open, allowing inflow of air through the opening 35, and this air will be drawn through the suction pipe 23 into the intake manifold 24 of the engine. When the float 22 is down, then air valve 36 will be closed; and then the air drawn with the liquid through pipe 14 will be drawn through the suction pipe 23 to the intake manifold. The air passage through air valve 36 is of such size as to pass substantially the same amount of air as is normally passed through pipe 14. The function of the inlet 35 and air valve 36 is two-fold; to provide approximately the same amount of air to be drawn into the engine manifold, as is provided through the pipe 14 when valve 36 is closed, so as to keep fairly or substantially uniform the supply of air (and therefore of combustible mixture) to the manifold; and to provide access of atmospheric pressure to the liquid in reservoir 15, so as to allow the liquid to flow out through pipe 30 to the carbureter; the liquid in the carbureter being exposed to atmospheric pressure. When valve 36 opens, the entrance of atmosphere to the reservoir prevents the further application of suction to the pipe 14; so that the opening of this valve stops the raising of

liquid and air through pipe 14. This takes place whenever the reservoir is full. When the liquid level falls so that the float 22 falls to the bottom of the reservoir, then the valve 36 is again closed and suction from the engine, which is always in connection with the top of the reservoir, is again applied to pipe 14 to lift liquid and air. The valve 36 controls the supply of liquid to the reservoir; it is the function of valve 21 merely to cut off the entrance of pipe 14 in such an emergency as when the tank 10 is above reservoir 15. Consequently, the valve 21 is not needed in a strictly stationary system but only in automobile systems, marine installations, and the like. The valve 36 normally alone controls the supply of liquid to the reservoir by merely allowing, or cutting off, access of atmospheric pressure to the reservoir; diverting or directing the engine suction from or to the pipe 14, without at any time actually cutting off the engine suction. It is the particular function of the check valve 31 to prevent back flow of the fuel from the carbureter to the service reservoir when the liquid in the reservoir is subjected to suction. If it were not for this check valve, this suction would pull the fuel back from the carbureter at the same time that it raised fuel in the pipe 14.

The complete operation of my system will be readily understood from the foregoing description. The applied suction draws a mixture of air and liquid through pipe 14 into the service reservoir 15, the liquid being held in that reservoir to supply the carbureter, and the air being drawn immediately into the engine manifold. The operation of raising liquid and air into the service reservoir will continue until the reservoir is filled; when the application of suction to pipe 14 will be discontinued. At this time, the entrance of atmospheric air will be allowed through air valve 36, supplying the engine with approximately the same amount of air as before, and putting atmospheric pressure on the liquid in the service reservoir. It is to be noted that, although the action of raising the liquid to reservoir 15 is intermittent, the application of suction and the flow of air through pipe 23, through one valve or the other, is fairly or substantially continuous. The carbureter draws its fuel from the service reservoir; and when the liquid level in the reservoir is lowered, the float operates the air valve 36 to cause the reservoir to be refilled. When the reservoir has been filled to the proper level, it is impossible, under any condition, to feed more liquid into the reservoir, as the float will hold the liquid feed port closed by operation of fuel valve 21. This is true even if tank 10 is temporarily higher than the reservoir. The liquid level in the service

reservoir is thus maintained with fair uniformity; thus maintaining a uniform pressure upon the carbureter at C; and thus causing satisfactory uniform operation of the carbureter.

The exact construction and structural relation of the various parts is of no general consequence in my invention. My invention applies in such situations as described without being limited to structural features except as stated in the appended claims. Many structural changes may be made; for instance, the service reservoir and carbureter may be structurally one unit; but these and other modifications will suggest themselves to persons skilled in the art.

Having described a preferred form of my invention, I claim:

1. In a liquid feed system, the combination of a liquid tank and a liquid reservoir above said tank, communication between the tank and the upper part of the reservoir, means for restrictedly admitting atmosphere to said communication, means for applying suction to the upper part of the reservoir, and automatic means for admitting atmosphere to the upper part of the reservoir to divert the application of suction from the said communication between the reservoir and tank.
2. In a liquid feed system, the combination of a liquid tank and a liquid reservoir above said tank, communication between the tank and the upper part of the reservoir, means for restrictedly admitting atmosphere to said communication, means for applying suction to the upper part of the reservoir, and float operated valve means for admitting atmosphere to the upper part of the reservoir, so that when the liquid level in the reservoir is low the admission of atmosphere is cut off and when the liquid level is high, the atmosphere is admitted.
3. In a liquid feed system, the combination of a liquid tank, a liquid reservoir above said tank, communication means between the upper part of the reservoir and the liquid tank, means to apply suction to the upper part of the reservoir, means to restrictedly admit a gas into the communication between the tank and the reservoir, and means controlled by the liquid level in the reservoir to open communication of atmosphere with the reservoir.
4. In a liquid feed system, the combination of a liquid tank, a liquid reservoir above said tank, communication means between the upper part of the reservoir and the liquid tank, means to apply suction to the upper part of the reservoir, means to restrictedly admit atmosphere into the communication between the tank and the reservoir; valve controlled means for admitting atmosphere to the reservoir, valve means for controlling the communication between the liquid tank and the reservoir, and a float in the reservoir for operating both of said valve means.
5. In a liquid fuel feed system for internal combustion engines, or the like, the combination of a liquid fuel tank, a liquid fuel reservoir above the tank, a carbureter, communication between the lower part of the reservoir and the carbureter to feed fuel from the reservoir to the carbureter by gravity, said communication including a check valve to prevent movement of the liquid fuel away from the carbureter into the reservoir, communication between the tank and the upper part of the reservoir, means to restrictedly admit atmosphere to said communication, means to apply suction to the upper part of the reservoir, said means embodying a communication between the upper part of the reservoir and the intake of the engine, communication between the upper part of the reservoir and atmosphere, valve means for controlling said communication, valve means for controlling the communication between the tank and the reservoir, a float in the reservoir, and operative connective means between the float and said valves to cause the second mentioned valve to be closed when the float is up and to open the first mentioned valve when the float is up and close it when the float is down.
6. In a liquid feed system, the combination of a liquid tank and a liquid reservoir above said tank, communication between the tank and the upper part of the reservoir, means for admitting atmosphere to said communication below the normal liquid level in the reservoir, means for applying suction to the upper part of the reservoir, and means for cutting off suction from the reservoir and admitting atmosphere thereto.
7. In a liquid feed system, the combination of a liquid tank, a liquid reservoir above said tank, communication between the tank and the reservoir, means to restrictedly admit atmosphere to said communication, means to apply suction to the upper part of the reservoir, the reservoir having an atmosphere inlet, a float, and valve means controlling the atmosphere inlet and operated by the float to open when the float reaches an upper position and to close when the float reaches a lower position.
8. In a liquid feed system, the combination of a liquid tank, a liquid reservoir above said tank, communication between the tank and the reservoir, means to restrictedly admit atmosphere to said communication, means to apply suction to the upper part of the reservoir, the reservoir having an atmosphere inlet, a float, valve means controlling the atmosphere inlet and operated by the

float to open when the float reaches an upper position and to close when the float reaches a lower position, and valve means controlling the entry of liquid to the reservoir operated by the float to be closed during the times when the float is in its said upper position.

9. In combination with a carbureter, a low level liquid fuel tank, a liquid fuel reservoir above the tank and in communication with the carbureter to supply it with fuel, communication between the tank and reservoir, means for restrictedly admitting atmosphere to said communication at a point 10 where the admitted atmosphere enters the upwardly moving column of liquid fuel moving from the tank to the reservoir, communication means to apply to said reservoir the suction which is applied to the carbureter to maintain a partial vacuum in the reservoir and to draw therefrom the air which enters it with the fuel, and means depending upon the level of liquid in the reservoir to discontinue the application of 15 suction to the reservoir.

10. In combination with a carbureter, a low level liquid fuel tank, a liquid fuel reservoir above the tank and in communication with the carbureter to supply it with fuel, communication between the tank and reservoir, means for restrictedly admitting atmosphere to said communication at a point 20 below the normal level of liquid fuel in the reservoir, communication means to apply to said reservoir the suction which is applied to the carbureter to maintain a partial vacuum in the reservoir and to draw therefrom the air which enters it with the fuel, an atmosphere communication port in the reservoir, and valve means depending upon the level of liquid in the reservoir to alternately open and close said port.

In witness that I claim the foregoing I have hereunto subscribed my name this 8th day of September, 1916.

CHARLES L. STOKES.
